UNITED STATES PATENT OFFICE

CECIL E. MITCHUM, OF KANSAS CITY, KANSAS

HEAT EXCHANGE APPARATUS FOR DAIRY EQUIPMENT

Application filed March 14, 1931. Serial No. 522,635.

The present invention relates to heat exchange apparatus, with particular reference to heating or cooling apparatus for use as a part of dairy equipment, and has for its primary object to devise an improved and more efficient construction for use in the cooling of milk after the pasteurizing process.

Accordingly, I have devised a novel and improved construction in which a chamber 10 is provided for the circulation of the heating or cooling medium, and the heat exchange caused to take place by the passage of the liquid to be treated through a plurality of tubular members extending through the heat exchange medium, in which operation the liquid is caused to be distributed and spread over the interior surfaces of the tubular members for producing as high a degree of efficiency in the heat exchange action as possible.

20 In the form herein shown, for illustrative purposes, the construction comprises a casing having inlet and outlet connections for the heat exchange medium, and tubular members extending in parallel relation through the casing, and having removable fluted elements at the mouths of the tubular members for effecting the proper distribution and spreading of the liquid over the interior surfaces of said tubular members.

30 It is also sought to provide a simple and practical construction, the parts of which may be maintained in a clean and sanitary condition, by removal of all parts necessary for this purpose, and affording access to the interior passages for a thorough cleaning of the same as conveniently as possible.

With the foregoing general objects in view, the invention will now be described by reference to the accompanying drawing illustrating one proposed embodiment of my improved construction, after which those features and combinations deemed to be novel will be set forth and claimed.

45 In the drawing—

Figure 1 is a side elevation, partly broken away, illustrating a heat exchange apparatus constructed in accordance with the present invention;

50 Figure 2 is a plan view of the same;

Figure 3 is a transverse section, taken on the line 3—3 of Figure 1;

Figure 4 is an enlarged detail sectional view, showing a portion of the upper end of the construction, with one of the liquid distributing elements; and

Figure 5 is a section on the line 5—5 of Figure 4.

Referring now to the said drawing in detail, this shows my improved construction as comprising a casing or drum 8 which is adapted to be supported either as a stand, or by means of hanger rods 9 in suspended relation, for which purpose straps 10 are attached to one end of the casing for attachment to said rods 9, as shown in Figures 1 and 2. The casing 8 may be made of any size, and with as many heating or cooling chambers 12 as desired, for which purpose the interior of the casing is divided by one or more partitions 13, as shown in Figure 1.

Each of the chambers 12 is provided with an inlet connection 14 and an outlet connection 15 for the circulation of the particular heat exchange medium which is to be employed. Preferably also the casing 8 is enclosed within a jacket 16 with insulation 17 to prevent any undue loss of heat, as well as to avoid undue frosting when in operation as a cooling apparatus.

The lower end of the casing 8 is provided with a head 18, and its upper end also provided with a head 19, and each head formed with openings for receiving the opposite ends of a plurality of tubular members 20 extending through corresponding openings in the partition 13, as illustrated in Figure 1. Above the upper head 19 the casing 8 is formed with a receiving basin 22, into which the milk or other liquid to be treated is allowed to flow by way of a discharge pipe 23, and in order that this milk or other liquid may be confined to sheet-like paths over the interior surfaces of the tubular members 20, the upper end of each of said tubular members is fitted with a cylindrical distributing element 24 having its lower end slightly tapered to fit removably into the upper end or mouth of the corresponding tube 20,

95 and also formed with a plurality of grooves 100

or flutes 25 for the passage of the liquid between the lower tapered ends of the element 24 and the inside surface of the tube 20. Each of the tubes 20 is also formed with a roll or bead 26 adjacent to its upper end and directly underlying the lower end of the element 24 in position to intercept the flow of liquid and render more certain the spreading or distributing effect of the liquid over the interior surface of the tubes.

As the milk or other liquid is discharged at the lower ends of the tubes 20, it is received in a circular basin 30 provided with a central discharge outlet 31 for connection 15 to an appropriate discharge conduit, the basin 30 being suspended by means of bolts 32 and wing nuts 33 whereby it is attached to laterally projecting lugs 34 at the lower end of the jacket 16.

20 In the usual operation of the apparatus, as a cooling means for milk after pasteurization, as a part of dairy equipment, any suitable cooling medium or agent, such as cold water, brine, or ammonia gas or liquid, is circulated through the compartments 12 by means of the connections 14 and 15, whereby the tubular members 20 are maintained in a properly chilled state. In the event of a heating action being required, either steam 25 or hot water or equivalent heating medium may be circulated through the said connections, in the same manner. As the flow of milk is caused to take place, by discharging the same into the upper receiving basin 22, 30 and allowing it to drain down through the tubular members 20, the milk is efficiently distributed, and caused to spread in sheet-like films over the interior surfaces of the tubes 20, thus providing a heat exchange relation of maximum efficiency between the milk and the heat exchange medium. This spread of the milk liquid is promoted by the action of the beads or rolls 26, which extend inwardly sufficiently to intercept any drops 40 of liquid not already adhering to the interior surface of the tubes. The milk or other liquid is thus thoroughly chilled by the time it reaches the lower ends of the tubular members 20 since none of the liquid is allowed 50 to simply fall through the interior of the tubes, or out of contact with the interior walls. The cooled milk is thus drained from the tubes into the bottom basin 30, and conducted off by way of the outlet 31.

55 An improved construction is thus provided, which is not only of a more efficient but also economical character as regards its operation, because the liquid is properly distributed into contact with the heat exchange surfaces, in an even, uniform manner, regardless of whether the apparatus is set in true vertical position or not. The heat exchange action is also carried out not only more effectively, but with less travel of the liquid than in many forms of apparatus now

in use requiring a more or less zigzag travel of the liquid undergoing treatment, and in this connection another advantage of the improved construction is its less disturbance of the cream line of the milk than is produced by the repeated baffling of the milk in structures operating to intermittently reverse the flow of the milk.

A further advantage of my present construction is its flexibility as it lends itself to a ready variation of the capacity of the particular units desired, and at the same time requires far less floor space than the other forms of equipment referred to. Furthermore, an important feature of advantage is the sanitary factor of the construction, the distributing elements 24, as well as the bottom receiving basin 30 being readily removable for cleaning purposes, and their removal leaving the ends of the tubular members 20 open for easy access for cleaning purposes. It will also be observed that all necessary aeration of the milk will be effected, since there is a natural draft of air created up through the tubular members and around the distributor elements 24, as induced by the warm condition of the milk which is being treated. This involves no undue exposure of the milk to contamination from the outside air since the flow of the milk through the apparatus is completely protected while such aeration takes place.

The outside jacket structure further increases the efficiency of the operation by the insulation afforded, and the unit as a whole is of an economical character to build, and correspondingly inexpensive to maintain.

While the foregoing illustrates what I now regard as the preferred form of construction for embodying the present improvements, I desire to be understood as reserving the right to make all such changes or modifications as may fairly fall within the scope of the appended claims.

What I claim is:

1. A heat exchange device for dairy equipment comprising a chamber having means for circulation of the heat exchange medium through said chamber, means providing a plurality of separate passages through the chamber for the liquid to be treated, and longitudinally fluted and slightly tapered elements fitted removably in the upper ends of said passages for distributing the flow of liquid to the inner surfaces thereof, the entrances to said passages being also provided with inwardly projecting means in the path of liquid flow for intercepting any free drops of liquid and causing same to adhere to the inner walls of said passages.

2. A heat exchange device for dairy equipment comprising a chamber having inlet and outlet connections for the heat exchange medium, a plurality of tubular members providing passages through said chamber for the

liquid to be treated, and means at the entrance to each of said passages for distributing the flow of liquid to the interior surfaces of said tubular members, each of said tubular members being formed with an internal annular bead adjacent its upper end in position to intercept the flow of liquid from said distributing means.

3. A heat exchange device for dairy equipment comprising an insulated upright casing having inlet and outlet connections for the heat exchange medium, a plurality of tubular members providing vertical passages through the medium for the flow of liquid to be treated, means at the entrances to said passages for distributing the flow of liquid to the inner surfaces of said tubular members, and a receiving basin provided with adjustable suspension means detachably connecting said basin with the lower end of said casing beneath the discharge ends of said tubular members.

In witness whereof I hereunto affix my signature.

CECIL E. MITCHUM.
